UNITED STATES PATENT OFFICE.

MILLARD FILLMORE BLAKE, OF MARTINSBURG, PENNSYLVANIA, ASSIGNOR
OF ONE-FOURTH TO JOHN S. BOWERS, OF SAME PLACE.

FREIGHT-CAR.

SPECIFICATION forming part of Letters Patent No. 600,631, dated March 15, 1898.

Application filed September 9, 1897. Serial No. 651,093. (No model.)

To all whom it may concern:

Be it known that I, MILLARD FILLMORE BLAKE, a citizen of the United States, residing at Martinsburg, in the county of Blair 5 and State of Pennsylvania, have invented certain new and useful Improvements in Freight-Cars; and I do declare the following to be a full, clear, and exact description of the invention, such as will enable others skilled in the art to which it appertains to make and use the same.

My invention has relation to dumping-cars; and the object is to provide a car which may be used either as an ordinary box-car, an ordinary dumping-car, or as a grain-dumping car.

With this object in view the invention consists of certain features of construction and combination of parts, which will be hereinafter fully described and claimed.

In the accompanying drawings, Figure 1 is a longitudinal vertical sectional view taken through the body of the car and showing the position the grain-doors and the end inclines and flaps are in when the car is used for the transportation of grain. Fig. 2 is a similar view showing the doors and inclines elevated to adapt the car for the transportation of other character of freight; and Fig. 3 is a cross-sectional view through one of the sides of the car, taken through the doorway.

In said drawings, 1 denotes the body of a box-car. 2 denotes the hinged floor, and 3 the mechanism for lowering the sections of the flooring to discharge the car of its contents. These parts may be of any well-known construction, but are identical in the present instance with the corresponding parts shown and described in Letters Patent No. 567,019, granted to me September 1, 1896, and a further description of the same will not be deemed necessary, as they form no part of my present invention.

A represents the grain-doors, one being in each side of the car-body near each end. These doors have eyes B, which are hung upon vertical hanger-rods C, secured to the inner sides of the car-body at the edge of the doorway, so that when not in use the doors 50 may be elevated and swung back and held in this position out of the way by means of hooks D, engaging pins d. The lower edge of each

door is provided with a flexible strip F, which when the door is closed lies upon the bottom of the floor and prevents the escape of grain 55 between the sill and the lower edge of the door.

At each end of the car is an incline G, which extends downwardly and has its lower edge in close proximity to the door-sill to feed the 60 grain close up to the doorway through which it is to be removed. The upper ends of these inclines are provided with eyes H, which are hung upon transverse rods E, secured at each end of the car-body, so that when the car is 65 not in use for transporting grain these inclines may be swung up and secured by hooks F', thus enlarging the capacity of the car.

Each incline G has secured above its upper edge to the end of the car a stiff flap, preferably made of rubber and fabric, and when the car is filled with grain these flaps K lie upon the grain, and, while incidentally protecting the same from dampness from the roof at the ends of the car, have for their main object the pressing of the grain downward, so that when it is removed either through the doors of the car or through the hinged bottom 75 none will stick or accumulate upon the inclines, thus enabling a car to be completely 80 emptied of its contents.

From the foregoing description, taken in connection with the accompanying drawings, the construction and operation of the invention will be readily understood without requiring further explanation.

A car built on these lines will answer as an ordinary box-car, an ordinary dumping-car for carrying coal, stone, &c., or as a grain-car, and is very efficient in either of the three uses 85 named.

Although I have specifically described the construction and relative arrangement of the several elements of my invention, I do not desire to be confined to the same, as such 95 changes or modifications may be made as clearly fall within the scope of my invention without departing from the spirit thereof.

Having thus described my invention, what I claim, and desire to secure by Letters Patent, is—

1. In a dumping-car, the combination with inclines arranged at the ends of the car, of stiff flaps secured above the upper edges of

the inclines and adapted to lie over the top surface of the grain and to be folded up when the inclines are elevated, substantially as set forth.

5 2. In a dumping-car, the combination with inclines hinged to the ends of the car, of stiff flaps secured to the ends of the car above the upper edges of the inclines, and means for holding the inclines raised, substantially as set forth.

10 3. In a car, the combination with inclines at the ends of the car and flaps secured above

the inclines and adapted to lie upon the grain contained in the car to protect the same from inclemencies of the weather and force it off the inclines when the car is being unloaded, substantially as set forth. 15

In testimony whereof I hereunto affix my signature in presence of two witnesses.

MILLARD FILLMORE BLAKE.
